UNITED STATES PATENT OFFICE.

JAMES E. WRIGHT, OF BAY CITY, MICHIGAN.

SHOT-SPREADING DEVICE FOR GUN-MUZZLES.

1,227,987.

Specification of Letters Patent.

Patented May 29, 1917.

Application filed August 30, 1916. Serial No. 117,649.

To all whom it may concern:

Be it known that I, JAMES E. WRIGHT, a citizen of the United States, residing at Bay City, in the county of Bay and State of Michigan, have invented certain new and useful Improvements in Shot-Spreading Devices for Gun-Muzzles; and I do hereby declare the following to be a full, clear, and exact description of the invention, such as will enable others skilled in the art to which it appertains to make and use the same.

This invention relates to guns and pertains more particularly to guns either of large or small caliber, adapted for firing a number of projectiles simultaneously. The improvement is more particularly for use in light or heavy artillery guns, shot guns, riot guns, trench guns and the like.

The object of the improvement is to provide a muzzle construction for guns, the muzzle being adapted to deflect the projectiles in such a manner that they will not scatter to any great extent in a vertical direction, but will spread widely in a horizontal direction.

The muzzle construction, which comprises my present improvement may be combined either with the barrel of the gun to form an integral part thereof, or it can be made detachable from the barrel.

A gun built in accordance with my improvement, as for example, a 12 gage shot gun loaded with twelve BB buckshot, spreads the shot to include an area fourteen inches high by eight feet wide at a distance of thirty yards.

With the above and certain other objects in view, which will appear later in the specification, my invention comprises the devices described, and the equivalents thereof.

In the drawings, Figure 1 represents a cannon, in side elevation, showing my improvement attached.

Fig. 2 is a part sectional top plan view of a gun-muzzle.

Fig. 3 is an end view of the muzzle.

Fig. 4 is a diagrammatic end view of the muzzle, showing the manner in which shot of relatively large size are discharged.

Fig. 5 is a side view of a shot gun embodying my improvement.

Fig. 6 is a diagrammatic end view of the muzzle of a gun showing the manner in which shot of smaller size are discharged.

As is clearly shown in the drawings, the improvement consists in providing the bar-

rel of a gun with a muzzle, which is flattened in a vertical direction and spread or widened in a horizontal direction.

1 represents the barrel of a cannon and 2 is its flattened muzzle.

Referring to Figs. 1 and 3, the width 3 of the flattened muzzle 2 is considerably greater than the height 4 of the muzzle opening. The muzzle preferably has flaring sides 5, 5 and a short parallel sided extremity 6, 6. In small arms, such as shot guns, the height of the muzzle opening is preferably just sufficient to permit the passage of a single projectile, as indicated diagrammatically in Fig. 4.

The muzzle 2 may be made integral with the barrel, or it may be removably secured thereto. When the muzzle is made removable, as shown in Fig. 2, it may be attached to the barrel by any suitable means, as for example by screw threads 7.

I do not, however, desire to confine myself to the use of any specific means for fastening the removable muzzle to the barrel.

While I have shown and described the improvement as applied to a cannon, it may, as above noted, be applied to a shot gun or equivalent fire-arm, as at 2^a in Fig. 5.

As has been previously stated, when my improvement is applied to small arms, such as shot guns, the vertical height of the muzzle opening is preferably just sufficient to permit a single projectile to pass, thus allowing a row of bullets to leave the muzzle simultaneously. The flaring sides 5, 5 permit the shot to spread, while the parallel sided walls 6, 6 prevent the shot spreading too far. The spread of the shot can thereby be made to suit the effective range of the gun.

In the case of a cannon the muzzle opening may be proportioned in the same way. However, projectiles of about three-eighths inch or larger in size may be employed in the cannon and the muzzle opening is in such case preferably so proportioned that its cross sectional area will be almost equal to the cross sectional area of the bore of the gun, thereby slightly "choking" the muzzle and effectively utilizing the propelling force of the explosive throughout the entire length of the barrel.

While I have shown and described the improvement as embodying a flattened muzzle of relatively short length (see Fig. 2), it is obvious that any less or greater length of

flattening can be adopted without departing from my invention.

Having thus described my invention, what I claim and desire to protect by Letters Patent is:

1. A gun barrel comprising a tube formed with a bore, the muzzle end of said tube being flattened to form a muzzle opening, the horizontal width of which is greater than its height, the height being sufficient to permit the passage of a single projectile, for the purposes set forth.

2. A gun barrel comprising a tube formed with a bore, the muzzle end of said tube being flattened to form a muzzle opening, the cross sectional area of which is slightly less than the cross sectional area of the bore, the

horizontal width of said opening being greater than its height, the height being sufficient to permit the passage of a single projectile, for the purposes set forth.

3. A gun barrel comprising a tube formed with a bore, the discharge end of said tube being flattened to form a spreading muzzle, said muzzle formed with outwardly flaring sides, intermediate its ends, and parallel sides near its extremity.

In testimony whereof, I affix my signature in presence of two witnesses.

JAMES E. WRIGHT.
